[57] CLAIM

The ornamental design of a track type key holder, as shown and described.

DESCRIPTION

FIG. 1 is a rear perspective view of a track type key holder showing my new design;

FIG. 2 is a rear elevational view thereof;

FIG. 3 is a front elevational view thereof;

FIG. 4 is a left side elevational view thereof taken from FIG. 3, the right side elevational view being the mirror image thereof;

FIG. 5 is a top plan view thereof; and,

FIG. 6 is a bottom plan view thereof.

The broken line showing of key rings and track connectors in FIG. 1 is for illustrative purposes and forms no part of the claimed design.
